UNITED STATES PATENT OFFICE.

WILLIAM F. PERSONS, OF CLEVELAND, OHIO, ASSIGNOR TO THE GUIDE MOTOR LAMP MANUFACTURING COMPANY, OF CLEVELAND, OHIO, A CORPORATION OF OHIO.

LAMP.

1,138,503.

Specification of Letters Patent.

Patented May 4, 1915.

Application filed March 2, 1914. Serial No. 821,895.

To all whom it may concern:

Be it known that I, WILLIAM F. PERSONS, a citizen of the United States, residing at Cleveland, in the county of Cuyahoga and 5 State of Ohio, have invented certain new and useful Improvements in Lamps, of which the following is a specification.

My invention relates to improvements in lamps, the present embodiment being particularly 10 designed and adapted for use in connection with automobile lamps, and relates to improved means for preventing the glare of headlights and search lights used in connection with motor vehicles.

15 The primary object of the invention is to provide an improved intercepting or shading medium or agent adapted to intercept certain rays of light between the source of illumination and certain reflecting portions 20 of the reflector thereby preventing the glare arising from this portion of the reflector ordinarily due to the direct reflection of such light as becomes the upwardly projecting rays in the field of illumination. The 25 present embodiment, at the same time, permits of the direct and effective passage of the downwardly reflected or projected rays of light for illuminating the roadway and directly reflected from the upper portions of 30 the reflector.

With the above mentioned and other ends in view, the invention consists in the novel construction, arrangement, and combination of parts, hereinafter described, illustrated 35 in one of its embodiments in the accompanying drawings, and particularly pointed out in the appended claim.

Referring to the drawings, Figure 1 is a vertical central sectional view of a lamp 40 reflector equipped with an incandescent lamp bulb embodying my invention. Fig. 2, is a modified form of bulb embodying my invention.

Similar numerals of reference designate 45 like parts throughout all the figures of the drawings.

The reflector 1, may be of any suitable and convenient form of construction and any suitable and convenient source of illumination 50 may be provided.

The intercepting or shading medium or agent 2, may comprise any suitable and convenient translucent material or medium and is interposed between the source of illumination 3, and that portion 1^a, of the reflector from which the offensive rays of light are projected or reflected. In the present instance, this shaded portion 1^a, of the reflector comprises the lower half of the same so that no glare arises from this portion of 55 the reflector ordinarily due to the direct reflection of light received from the source of illumination on this portion of the reflector and from thence reflected and projected upwardly into the upper portion of the field of 60 illumination.

In carrying my invention into effect in connection with an ordinary incandescent filament, 3, and lamp bulb 4, I provide the lower portion or half of the bulb 4, with a 65 suitable translucent shading or intercepting agent 2, this shading or intercepting medium being preferably of a suitable color, such as ruby red, or the like, adapted to absorb and break up the rays of light as well as shade 70 the part or portion 1^a, of the reflector in such a manner as to prevent a glare. The lower half or portion 1^a, of the bulb is preferably first ground on its exterior to provide 75 a roughened and irregular surface to better 80 receive and carry the coloring material. If desired, the intercepting or shading medium 2, may be extended to form an annular extension 2^a, about the base of the bulb as shown in Fig. 2 of the drawings. 85

Upon reference to Fig. 1 of the drawings, it will be seen that only the upwardly extending rays of light are permitted to directly strike against and be reflected by the upper portion of the reflector and these rays 90 of light are thence refracted and projected into downwardly and forwardly extending rays of light to become the lower portion of the projected field to illuminate the roadway while the upper rays of light are broken up 95 or diffused and the lower portion 1^a, of the reflector is thus deprived of its glaring properties.

From the foregoing description, taken in connection with the accompanying draw- 100

ings, the advantages and operation of my invention will be readily understood.

Having thus described one of the embodiments of my invention, what I claim and desire to secure by Letters Patent, is,—

In a projector, the combination of a reflector adapted to project an approximately concentrated beam of light, and an incandescent lamp comprising a filament and a bulb having its surface between said fila-

ment and the lower portion of said reflector roughened and colored to prevent reflection of rays of light into the upper portion of the projected field.

In testimony whereof I have affixed my 15 signature in presence of two witnesses.

WILLIAM F. PERSONS.
